[57] **CLAIM**

The ornamental design for a belt buckle, as shown and described.

DESCRIPTION

FIG. 1 is a front plan view of a belt buckle showing my new design;

FIG. 2 is a bottom view of the buckle as shown in FIG. 1 depicting the belt attaching loop on the right and the tongue for insertion into holes in the belt on the left;

FIG. 3 is a left side view of the buckle of FIG. 1 depicting the tongue and loop for the belt;

FIG. 4 is a right side view of the buckle of FIG. 1 depicting the tongue and loop for the belt;

FIG. 5 is a perspective view of the buckle of FIG. 1;

FIG. 6 is a rear plan view of the buckle of FIG. 1; and,

FIG. 7 is a cross-section view of a portion of FIG. 5.

The broken line showing of indicia, in the five circles surrounding the star, is for illustrative purposes only and forms no part of the claimed design.
